CLAIM

The ornamental design for a surgical scrub V-neck shirt, as shown and described.

DESCRIPTION

FIG. 1 is a front view of a surgical scrub V-neck shirt with panels showing our new design;

FIG. 2 is a rear view of the design shown in FIG. 1; and,

FIG. 3 is a front view of the design shown in FIG. 1.

The broken line showing of a collar in FIGS. 1-3, a rear mesh portion in FIG. 2, and a pocket in FIG. 3 are for the purpose of illustrating environmental structures and form no part of the claimed design.
